[57] CLAIM

The ornamental design for a housing for a floor cleaning machine, as shown and described.

DESCRIPTION

FIG. 1 is a top, front and side perspective view of a housing for a floor cleaning machine showing my new design;

FIG. 2 is a side elevational view thereof, the opposite side being a mirror image;

FIG. 3 is a top plan view thereof;

FIG. 4 is a front elevational view thereof; and

FIG. 5 is a rear elevational view thereof.

The undisclosed bottom is flat and unornamented.

*Fig. 1**Fig. 4**Fig. 2**Fig. 3**Fig. 5*
